WASTE AND OVERFLOW FITTINGS FOR LAVATORY WASH BASINS, BATHTUBS, KITCHEN SINKS, AND THE LIKE

Application filed May 24, 1929. Serial No. 365,658.

The present invention relates to an improvement in waste and overflow fittings for lavatory wash basins, bath tubs, kitchen sinks, and the like, and my object in general is to provide a valved fitting and assembly of parts which may be easily and quickly installed, and also readily separated, cleaned or repaired, after installation has taken place.

In the accompanying drawings, Fig. 1 is a sectional view of the device attached to the wall of a vessel, and Fig. 2 is a front view of the overflow and controlling parts of the device. Fig. 3 is an elevation of the clamping ring for supporting the overflow plate. Fig. 4 is a perspective view of the valve. Fig. 5 is a horizontal section of the valve within the T-fitting. Fig. 6 is an enlarged sectional view on line 6-6 of Fig. 7 of the overflow portions and controlling handle of the device. Fig. 7 is a horizontal section of the same parts on line 7-7 of Fig. 6. Fig. 8 is a sectional view on line 8-8 of Fig. 7, showing the spring-pressed detent for locking the controlling handle. Fig. 9 is a sectional view corresponding to Fig. 1, of a modified form of the invention, and Fig. 10 is a front sectional view on line 10-10 of Fig. 9. Fig. 11 is a sectional view horizontally of the elbow on line 11-11 of Fig. 9. Fig. 12 is a sectional view on line 12-12 of Fig. 10, of the lever and detent device. Fig. 13 is a sectional view horizontally through the overflow and drain fitting and the valve therein, on line 13-13 of Fig. 9.

The invention involves the use of an overflow head or elbow A which is adapted to be clamped against the outer wall by a basin, tub, or other vessel B, having an overflow opening 2 therein. Such vessels are also provided with a drain opening in the bottom thereof (not shown) to which a drain pipe C is connected, all as known to those skilled in the art. Pipe C is coupled to a side branch 3 of a pipe fitting D. This fitting has vertical branches 4 and 5, respectively, to which an overflow pipe 6 and discharge pipe 7, are adjustably coupled by gaskets and nuts 8 and 9 respectively. Overflow pipe 6 is connected with the bottom end of

overflow elbow A, and the elbow itself is clamped to the wall of vessel B by a pair of screws 10 which pass through a clamping ring or equivalent member E placed against the front face of the vessel wall opposite overflow opening 2. Screws 10 connect with a pair of internal lugs 11 and 12 respectively cast integral with elbow A, and lug 12 on this elbow includes a cylindrical bearing portion 14 which extends forwardly 55 into opening 2. A sealing gasket 15 is usually interposed between elbow A and the wall of vessel B.

A perforated cover or strainer plate F is fastened to a bridge or spanning portion 16 of clamping member E, a central screw 17 being provided for that purpose. The strainer plate may therefore be attached and replaced without disconnecting or releasing the overflow elbow or disconnecting parts 60 clamped upon the wall of the vessel, including the controlling handle G which is pivotally mounted upon the cylindrical projection 14 extending forwardly from lug 12 on elbow A.

Handle G is adapted to be rotated approximately 90° and extends through a slot 18 within a border edge or annular flange 19 of strainer plate F, see Fig. 6. Handle G is of angular formation or provided with an offset 65 or arm 20 having an opening or open bearing 21 adapted to sleeve over cylindrical projection 14 which is located near one side and off-center of the mouth of elbow A. The handle or controlling lever G is also provided with an operating extension 22 which is projected at an angle into elbow A where coupling member 23 is adapted to be connected therewith directly in line with overflow pipe 6.

A rod or link 24 is screwed or otherwise attached to member 23, and the lower extremity of the said rod or link is formed with an eye 25 to provide a suspensory connection for a valve H movable vertically within the T-fitting D opposite the lateral drain opening 26 within branch 3. Valve H includes a circular enlargement 27 which is adapted to seat against the border edges of drain opening 26 to close the same when the valve is 100

lowered within fitting D, and an inclined rib 28 forming an integral part of fitting D directly opposite drain opening 26 serves to guide and press the valve by its own weight 5 against the valve seat when the valve is lowered within the fitting. To promote that purpose valve H is formed with a channeled head 29 to embrace and engage the inclined guide rib 28.

10 As constructed valve H is of smaller dimensions or cross section than the chambers within fitting D, thereby permitting the overflow waste to pass to discharge pipe 7 when the valve is either raised or lowered within fitting D.

15 Seating of valve H is by gravity, and therefore when the controlling lever or handle G is turned on its pivot to the dotted position shown in Fig. 6 to raise and open valve H 20 in respect to drain opening 26, it is desirable at times to lock the lever in that shifted position. This is accomplished by a spring-pressed plunger or detent 30 carried by lever G, and this plunger may extend radially of 25 the lever opposite the rounded surface of lug 12 on elbow A. Lug 12 may be provided with a depression or socket 31 to receive the plunger when the handle is turned to its limit of movement as indicated by the dotted lines in 30 Fig. 6. The structural details of the pivot lug and the spring-pressed detent are shown more clearly in full lines in Fig. 8.

35 Figs. 9 to 13 inclusive, represent a modified structure. Thus, the T-fitting D' is constructed to seat a valve H' having a circular sealing face of the same curvature as the inner wall of the fitting. This valve is also formed with a channeled portion 29' to embrace an inclined rib 28' within fitting D'. 40 The valve is connected by a link or rod 24' to a crank extension 22' on a lever G', having a spring-pressed plunger 30' extending forwardly where it is adapted to press against the inner face of a clamping bar E'. Lever 45 G' is supported by a pivot lug 14' at one side of the mouth of the elbow, and the lever is locked or held at the limits of its arc movement when plunger 30' engages depressions or notches 31' in bar E'. Otherwise, this 50 structure is similar to the one shown in Figs. 1 to 8, inclusive.

1 What I claim, is:

1. In an overflow and drain fitting for a 55 bath tub, lavatory basin, sink, or like vessel, an overflow elbow having an integral pivot lug within its mouth, an overflow and drain fitting connected with said elbow having a valve therein, and means pivotally supported by said lug for operating said valve.

60 2. In an overflow and drain fitting for a 100 bath tub, lavatory basin, sink, or like vessel, an overflow elbow having a pair of attachment lugs internally at opposite sides thereof, a valve controlling lever pivotally supported 105 upon one of said lugs, and an overflow and

110 drain fitting connected to said elbow having a valve therein connected to said lever.

115 3. In an overflow and drain fitting for a 115 bath tub, lavatory basin, sink, or like vessel, an overflow elbow, a clamping member for 120 said elbow, clamping screws for said member connected interiorly with said elbow at opposite sides thereof, a lever fulcrumed at one side of said elbow at its point of connection with one of said clamping screws, and an 125 overflow and drain fitting having a valve 130 therein operably connected to said lever.

135 4. In an overflow and drain fitting for a 135 bath tub, lavatory basin, sink, or like vessel, an overflow elbow, an overflow and drain 140 fitting connected to said elbow, a valve within 145 said fitting, and operating means for said valve, including a pivoted lever and a spring-pressed detent to lock the lever and valve in 150 open position.

155 5. In an overflow and drain fitting for a 155 bath tub, lavatory basin, sink, or like vessel, an overflow elbow and a clamping member 160 therefor, a lever pivotally supported opposite 165 said clamping member, a detent associated with said lever to hold the same in an open 170 position, an overflow and drain fitting connected to said elbow, and a valve within said 175 fitting having lift connection with said lever.

180 6. In an overflow and drain fitting for a 180 bath tub, lavatory basin, sink, or like vessel, an overflow elbow having a pair of attachment 185 lugs, a clamping member and screws 190 adapted to connect with said lugs, a cover plate attached to said clamping member, a lever pivotally supported at one side of said 195 elbow where connected to said clamping member, a spring-pressed detent for holding said lever in an open position, and an overflow and 200 drain fitting containing a valve operably connected to said lever.

205 In testimony whereof I affix my signature.
CHARLES F. SCHULTIS.
